COMBINATION PENCIL STAND AND SHARPENER

Filed June 17, 1929

FIG. 1.

FIG. 2.

Inventor
George Potstada

By *Baldwin Hall*

Attorney

UNITED STATES PATENT OFFICE

GEORGE POTSTADA, OF OAKLAND, CALIFORNIA

COMBINATION PENCIL STAND AND SHARPENER

Application filed June 17, 1929. Serial No. 371,361.

This invention relates to improvements in pencil sharpeners and more particularly to the pencil sharpener, and pencil stand combined.

5 Among the objects of the invention are to combine and arrange a pencil sharpener within a supporting base or stand in such a manner that the pencils can be sharpened by rotating it within the base without breaking 10 the lead.

Another object is to provide a stand for holding the pencil upright when not in use, and to catch and retain the shavings descending from the sharpener.

15 Other objects and advantages will appear as this description proceeds.

In this specification and the accompanying drawings the invention is shown in the form considered the best. But I do not wish 20 to be understood as confining it to this form because it may be embodied in other forms. It is also to be understood that in, and by the 25 claim following the description it is desired to cover the invention in whatsoever form it may be embodied.

In the accompanying one sheet of drawing,

Figure 1 is a front elevation of a combined pencil sharpener and base constructed in accordance with this invention, with parts 30 broken away in cross section to disclose the interrelation of parts.

Figure 2 is a vertical section of the same.

In detail the construction illustrated in the drawings comprises: A hollow base 1 of any 35 desired form suitably shaped and ornamented to make an attractive writing accessory. The lower portion of the base is closed by the sliding door 2, adapted to retain chips from the pencil sharpening operation until it is desired to slide the door out of the base for the purpose of discharging said chips.

The base has a vertical columnar extension 3 with a restricted top opening 4, the axis of which is slightly oblique to the vertical axis of the column 3.

50 A conventional blade pencil sharpener having a conical opening 5 is mounted within the column 3. The upper edge of the shell of the sharpener 6 abuts an internal shoulder at 7 to axially align the conical opening 5

with the cylindrical opening 4. One side of the body 6 is milled away to receive the blade 8 held to the shell 6 by the screw 9. The bevelled cutting edge of the blade 8 is set tangentially to the conical perimeter of the 55 opening 5.

The shell 6 is held in position against the shoulder 7 in any suitable manner, to permit renewal or replacement of the sharpener, such as the set screw 10 threaded into the base 1 at an angle so that it can be operated by a 60 screw driver inserted in the hollow bottom of the base.

This invention operates substantially as follows:

The end of the pencil to be sharpened is inserted through the opening 4 until it engages the cutting edge of the obliquely set blade 8. The base 1 is held with one hand while the pencil is gently rotated between the thumb and forefingers of the other hand, preferably holding the pencil by the extreme end. By gently forcing the pencil inward as it is rotated the pencil is gradually pointed by first cutting away the pencil wood until 75 the lead is exposed, then delicately turning the pencil until the lead is brought to the desired sharpness.

The shavings cut from the wood of the pencil curl outwardly from the blade 8 and drop into the hollow base 1. The dust from the lead being sharpened drops from the lower opening 11 of the center opening 5.

After the new pencil has received its first sharpening, it can be returned to the opening 4, wherein it is retained at a convenient angle for reuse. Each time the pencil is restored to the base it can be given a slight turn which keeps it constantly sharpened for ready use. The angle at which the pencil projects from the opening 4 makes it convenient to be grasped by the writer, thus keeping the pencil always within easy and convenient reach and in perfect writing condition.

The base 1 may be made of heavy material to serve as a paper weight, or other utility.

A number of sharpeners may be grouped in a single base to take care of pencils of different color or quality.

The chips can be removed from the hollow base 1 by sliding the door 2 outwardly and emptying the base.

Having thus described this invention, what I claim and desire to secure by Letters Patent is—

A stand of the class described, comprising a hollow pencil holder set at an angle to the perpendicular, and flaring outwardly at its lower end to form a base, a pencil sharpener unit adapted to be inserted into said holder through said base, a shoulder in said holder adapted to limit the upward travel of the pencil sharpener, means to secure said sharpener in said holder, and a slidable door in said base adapted to retain shavings and lead dust.

In testimony whereof I have hereunto set my hand this 12th day of June, A. D. 1929.

GEORGE POTSTADA.
